DEICING APPARATUS FOR AIRPLANE PROPELLEES

Thomas L. Siebenthaler, Kansas City, Mo., assignor to Thos. L. Siebenthaler Manufacturing Company, Kansas City, Mo., a corporation of Missouri

Application December 7, 1937, Serial No. 178,568

9 Claims. (Cl. 244—134)

This invention relates to airplane propeller assemblies and has for its primary object the provision of structure therein for applying ice preventing liquid to the propeller blades.

It is well-known in this art that due to the tremendous vibration encountered in airplane propeller assemblies, and the difficulty of mounting a large number of parts thereon, that it has heretofore been one of the industries' greatest problems to satisfactorily deposit ice preventing liquid on propeller blades without the depositing elements being rendered useless after a few hours' service.

This invention has for its salient object therefore, the provision of liquid applying structure that is made up of exceptionally few parts, all of which are specially designed to cooperate with the propeller assembly and to overcome the forces of vibration, torque and burdensome weight.

An even further object of the invention is to provide in liquid applying structure for airplane propeller assemblies, a specially formed distributor shell and uniquely arranged and created mounting brackets therefore, all of which may be associated with the propeller blades as to operate efficiently for a relatively long period of time.

A still further aim of this invention is the provision of means for mounting a liquid applying device to airplane propeller hubs, which means incorporates resilient elements for absorbing the shock, vibration and torque which would be transmitted to the liquid applying structure if brackets embodying this invention were not utilized.

A large number of minor objects are contemplated and the same will become apparent during the course of the following specification, referring to the accompanying drawings wherein:

Figure 1 is a side elevation of an airplane propeller assembly showing the liquid applying structure, made in accordance with this invention, in the operative position.

Fig. 2 is a front view of the same.

Fig. 3 is an enlarged fragmentary rear elevational view of a propeller assembly showing the liquid applying structure mounted thereon.

Fig. 4 is a perspective view of the distributor shell forming one of the elements of the liquid applying structure.

Fig. 5 is a fragmentary detailed sectional view through a portion of the said shell taken on line V—V of Fig. 4.

Fig. 6 is an enlarged irregular cross-sectional view through the propeller assembly taken on

line VI—VI of Fig. 3 and looking in the direction of the arrows.

Fig. 7 is an enlarged detailed cross-sectional view through one of the mounting brackets, disclosing clearly the resilient bearings therein.

Fig. 8 is a perspective view of a bracket yoke.

Fig. 9 is a perspective view of one of the resilient bearings removed from its operative position.

Fig. 10 is a fragmentary detailed view through an airplane propeller assembly, illustrating a modified type of mounting bracket, and,

Fig. 11 is an enlarged fragmentary detailed view taken on line XI—XI of Fig. 10.

The simplicity of the structure embodying the preferred form of this invention will at once become apparent to one skilled in the art, and it will also be clear that the propeller assembly with which the liquid applying structure is associated, may comprise the conventional hub 14 in which is secured a plurality of propellers 16, each of which extends radially outward from an axis of rotation which is on the longitudinal center of drive shaft 18. Propellers 16 in this instance, are shown in a fragmentary manner, but the plane of rotation is substantially at right angles to drive shaft 18 and intersects at least a portion of all of blades 16.

Hub 14 is usually formed of two castings, each of which has an ear projected therefrom and through which ears is passed a securing bolt or similar element, 22, which may be used in an advantageous manner as more fully hereinafter set down.

A nose piece 24 is usually secured to the propeller assembly in front of the same and on the longitudinal center line, and in this instance, said nose piece may be an aluminum spinning that is arcuate in cross section and generally dome-shaped. This nose piece 24 is secured to a collar 26 that is affixed to the hereinafter described liquid applying structure.

The means for actually applying the liquid which prevents the formation of ice on propeller blades 16, comprises a distributor shell 28 that is dish-shaped to have a bottom 30 and an annular side wall 32, provided with notches 34. Bottom 30 has a hole 36 formed therethrough for the passage of drive shaft 18, and an annular reservoir 38 is formed by bottom 30 of shell 28 at the edge thereof which defines hole 36. This reservoir 38 is in the form of an annular channel into which is introduced ice preventing liquid through tube 40 which extends from any suitable source of supply, not here shown. The open side of channel 38 is continuous and concentric to

the axis of rotation of drive shaft 18 and therefore liquid may be supplied to the reservoir as the propeller assembly is rotating.

Distributor shell 28 has a number of conduits 5 formed in the bottom and side wall thereof when the shell is cast. These conduits 62 are in communication at their one end with reservoir 28 and extend to a point adjacent to each notch 34 respectively.

10 The outlet ports 66 are in the plane of rotation of the propeller blades and in front of the respective blades so that as liquid is ejected therefrom, it will be caught by the blade as it travels. Centrifugal force will evenly distribute the liquid 15 over the surface of the propeller blade and to the end thereof so that a film of ice preventing liquid may be maintained at all times.

16 From the immediately foregoing, it will be apparent that shell 28 provides in a unitary member, the conduits and reservoir which are so essential to structures of the kind embodying this invention. It is only necessary to effectively fasten shell 28 in place to complete the combination and the means for securing this shell in the 20 operative position comprises a series, or plurality of brackets, best shown in Fig. 3. These brackets are secured to hub 14 in a novel manner and they are disposed between propeller blades 16. The brackets engage the inner face of wall 32 of shell 28 25 so that the smooth outer surface of shell 28 remains to overcome wind resistance.

26 Each of the series of brackets just mentioned, is identical and comprises a yoke 46 which presents opposed sides 48 through which is formed 30 windows 50. The back of yoke 46 should be arched to conform to the contour of the inner 35 face of shell 28 and a shoulder 52 is formed thereon to engage the edge of annular wall 32. This shoulder limits the inward movement of yoke 46 40 during assembly and leaves a portion thereof projected beyond wall 32 for the purpose of engaging ring 26.

45 A bolt 54 secures together yoke 46 and shell 28 and a similar bolt 56 secures together yoke 46 and ring 26. After these bolts are in position, a locking member 58 pivotally mounted as at 59, 50 is swung into engagement with the heads thereof to prevent accidental loosening. Thus, nose piece 24 and shell 28 are secured together and cooperate to house hub 14 and a portion of each propeller blade 16.

55 A resilient bearing member 60, made in accordance with the teachings of U. S. Letters Patent Nos. 1,452,693; 1,548,048; 1,996,210 and others, is secured to side walls 48 of yoke 46 so that the resilient rubber elements 62 thereof, may support the short shaft, or bolt 64 as shown in Fig. 7. A bushing 66 should be carried by element 62 so as to effectively journal bolt 64.

60 The axes of bolts 64 extending from side to side of yoke 46, are on the planes with the outer faces of ears 20 of hub 14, and because of this relation a pair of links 68 may be disposed in the manner illustrated. Each link 68 has an opening 65 70 therethrough to receive the bolt 12 which fastens together the two ears or portions of hub 14. A tubular portion 74 of link 68 receives bolt 64 so that when the parts are assembled, links 68 becomes the only metallic connection between hub 14 and the liquid applying structure.

70 So mounted, the distributor shell 28 and associated parts, insures dampening the major part of the vibration which would otherwise be transmitted from the drive shaft and hub 16 and 14 75 respectively.

Figs. 10 and 11 illustrate a modified form of the invention and in this instance, a U-shaped bracket 100 is employed. A rubber facing 102 is directly secured to bracket 100 and then a plate 104, vulcanized to one side of facing 102. Bolts 5 106 secure together shell 28 and ring 26 in the same way as before set down, and rubber 102 becomes the vibration dampening element.

10 The use of two mounting brackets between propeller blades 16 as indicated by Fig. 3, will 15 impart a stabilizing, yielding and effective support for shell 28, and there will be no tendency for any element of the liquid applying structure to loosen or free itself from the propeller assembly during operation.

15 All of the parts described above, should be made of light metal, such as aluminum alloy, so that the weight added will not be objectionable.

20 The operation of all the parts mentioned and shown in the drawings is clear to anyone skilled in the art, and while the invention has been illustrated and shown in a specific manner, it is desired to be limited only by the scope of the appended claims.

25 Having thus described the invention, what is claimed as new and desired to be secured by Letters Patent is:

1. In an airplane propeller assembly having a hub and a plurality of propeller blades extending radially from an axis of rotation, the combination of structure for applying ice preventing liquid to the propeller blades, comprising a dish-shaped distributor shell having a bottom and an annular side wall mounted on the hub and forming a liquid reservoir in said bottom, and a plurality of conduits in said side wall, said reservoir being adapted to receive a supply of liquid as the entire assembly is being rotated, said conduits each being in communication with the reservoir at one end and having the other end in the plane of rotation of the propeller blades and in front of the respective propeller blades.

- said other ends adjacent to the said notches whereby the ice preventing liquid is freed in the path of rotation of the propeller blades.
4. In an airplane propeller assembly having a hub and a plurality of propeller blades extending radially from an axis of rotation, the combination of structure for applying ice preventing liquid to the propeller blades, comprising a distributor shell having a liquid reservoir and a plurality of conduits formed in the body thereof, said conduits being in communication with the reservoir and disposed to direct liquid therefrom into the plane of rotation of said propeller blades; and a plurality of brackets connecting the distributor shell with the hub, said brackets being arranged around the axis of rotation in substantially opposed relation.
5. In an airplane propeller assembly having a hub and a plurality of propeller blades extending radially from an axis of rotation, the combination of structure for applying ice preventing liquid to the propeller blades, comprising a distributor shell having a liquid reservoir and a plurality of conduits formed therein, said conduits being in communication with the reservoir and disposed to direct liquid therefrom into the plane of rotation of said propeller blades, and a plurality of brackets connecting the distributor shell with the hub, said brackets being arranged around the axis of rotation in substantially opposed relation, said brackets having resilient bearing mountings therein to yieldably hold said distributor shell in the operative position.
6. In an airplane propeller assembly having a hub and a plurality of propeller blades extending radially from an axis of rotation, the combination of structure for applying ice preventing liquid to the propeller blades, comprising a dish-shaped distributor shell having an annular liquid reservoir formed in the bottom, and a plurality of conduits formed in the body of the bottom and annular side; and a series of brackets connecting the distributor shell with the hub, said brackets being in engagement with the inner face of the side of said dish-shaped shell and in connection with said hub between the propellers.
7. In an airplane propeller assembly having a hub and a plurality of propeller blades extending radially from an axis of rotation, the combination of structure for applying ice preventing

liquid to the propeller blades, comprising a dish-shaped distributor shell having an annular liquid reservoir formed in the bottom, and a plurality of conduits formed within the bottom and annular side; and a series of brackets connecting the distributor shell with the hub, said brackets being in engagement with the inner face of the side of said dish-shaped shell and in connection with said hub between the propellers, each of said brackets comprising a yoke, a resilient bearing carried by the yoke, and a link joining the hub and said resilient bearing.

8. In an airplane propeller assembly having a hub and a plurality of propeller blades extending radially from an axis of rotation, the combination of structure for applying ice preventing liquid to the propeller blades, comprising a dish-shaped distributor shell having an annular liquid reservoir formed in the bottom, and a plurality of conduits formed within the bottom and annular side; and a series of brackets connecting the distributor shell with the hub, said brackets being in engagement with the inner face of the side of said dish-shaped shell and in connection with said hub between the propellers, each of said brackets comprising a yoke, opposed resilient bearings carried by the yoke, a shaft journaled in said bearings, and a link joining the shaft and the hub.

9. In an airplane propeller assembly having a hub and a plurality of propeller blades extending radially from an axis of rotation, the combination of structure for applying ice preventing liquid to the propeller blades, comprising a dish-shaped distributor shell having an annular liquid reservoir formed in the bottom, and a plurality of conduits formed within the bottom and annular side; and a series of brackets connecting the distributor shell with the hub, said brackets being in engagement with the inner face of the side of said dish-shaped shell and in connection with said hub between the propellers, each of said brackets comprising a yoke, opposed resilient bearings carried by the yoke, a shaft journaled in said bearings, and a link joining the shaft and the hub, said link having a tubular portion at one end, said shaft being extended through said tubular portion.
